UNITED STATES PATENT OFFICE

FRANK LA GRANDE, OF COYTESVILLE, NEW JERSEY, ASSIGNOR TO PARAMOUNT PUBLIX CORPORATION, OF NEW YORK, N. Y., A CORPORATION OF NEW YORK

SOUND-PICTURE PRINTER

Application filed September 25, 1929. Serial No. 394,946.

This invention relates to the printing of sound motion pictures and more particularly to certain improvements in sound picture printers which simplify and facilitate the printing of sound picture positives, of the type in which the sound track is located at the edge of the same film that carries the action, from two separate negative films carrying, respectively, the action and the sound.

10 In the drawings:

Fig. 1 is a view taken on the line 1—1 of Fig. 2 showing the general features of a motion picture printing machine to which the present invention has been applied;

15 Fig. 2 is a sectional elevational view on the line 2—2 of Fig. 1;

Fig. 3 is a front elevation of the printing mechanism shown in Fig. 1;

20 Fig. 4 is a section on the line 4—4 of Fig. 1;

Fig. 5 is a detail view of the masking mechanism of Fig. 1 with the parts in a different position;

Fig. 6 is a view similar to Fig. 3 showing the sound mask in masking position;

25 Fig. 7 is a view of a fragment of a positive film with the sound track printed thereon; and

Fig. 8 is a similar view of the same film showing the addition of the action thereto.

30 Referring to the drawings in detail, the printer shown in Fig. 1 comprises lamp house casting 1 in the chamber of which, as will be understood, is mounted an incandescent lamp, not shown. Adjacent the lamp house

35 casting 1 is a connecting portion comprised of upper and lower walls 2 and 3, respectively, and side walls 4, the opening between these walls being in communication with the chamber of the lamp house 1 and forming a light

40 conduit to the printing aperture hereinafter referred to. The walls 2, 3 and 4 merge into a hollow cylindric casing portion 5 extending outwardly therefrom. The cylindric casing portion 5 has a horizontal bore 6 which is in the plane of the light conduit formed by the walls 2, 3 and 4 and opens thereto.

45 Passing transversely across the light conduit is a sprocket shaft 7, this sprocket shaft carrying a pair of spaced sprocket wheels 8 and 9 which are disposed in line with the

light conduit. At the opposite sides of the sprockets 8 and 9 from the lamp house casting 1 there is provided in the cylindric case 5 a rectangular opening or cut through which the sprockets extend to engage 55 the films which are shown at 10 and 11.

A curved plate 12 is secured in the bore 6 below the rectangular cut through which the teeth of the sprockets extend and extends upwardly beyond the lower edge thereof to provide the lower edge of the printing aperture as shown at 13.

Above the printing aperture is a curved block 14 suitably secured to the upper wall 2 by screws 15. This block is provided on its underside with a plate or bracket 16 carrying a pivot 17 on which are mounted sound mask 18 and action mask 19, each in the form of a curved plate at the printing aperture 13. Secured to the sound mask 18 and rotatable 70 on the pivot 17 is a pinion 20, while secured to the action mask 19 and rotatable on the pivot 17 is a pinion 21.

The bracket 16 to the rear of the pivot 17 is provided with another pivot 22 on which are pivoted for independent motion toothed segments 23 and 24, the segment 23 cooperating with pinion 20 and segment 24 with pinion 21, so that when the segment 23 is rocked on its pivot the sound mask will be moved downwardly away from the light aperture and when the sector 24 is operated the action mask 19 will be moved downwardly away from the light aperture. It will be appreciated that the action mask 19 and sound mask 18 are movable independently of each other.

80 The sector 23 is provided with a rearward extension 25 having a lug 26 to which is secured one end of a coil spring 27, the other end of which bears against the block 14, this spring being so mounted that it will maintain the sound mask in masking position. Likewise the sector 24 is provided with a rearward extension 28 having a lug 29 to which is secured one end of a coil spring 30, the other end of which is secured to the block 14, this spring being so disposed as normally to maintain the action mask in masking position.

From the description thus far given, it will be seen that if a negative film 10 and positive film 11 be moved by the sprockets 8 and 9 past the light aperture 13 no exposure will be made by light from the lamp house 1 passing through the light aperture 31 unless one or the other of the masks 18 and 19 is moved out of the light aperture 13.

To effect selective movement of these masks out of the light aperture two adjusting screws 32 and 33 are provided at the top of the block 14, the lower ends of these screws projecting through the block and the screw 32 engaging the extension 28 on the sector 24, while the screw 33 engages extension 25 on the sector 23.

In operation, assuming that the sound track is first to be printed from a negative 10 on which the sound has been photographed, this negative and an unexposed positive 11 are threaded into the machine upon the sprockets 8 and 9. The screw 33 is then screwed downwardly sufficiently to move the segment 23 against the action of its spring 27 and through the pinion 20 to move the sound mask 18 out of the light aperture as illustrated in Fig. 1. The films are then run through by rotation of sprockets 8 and 9 until the sound has been recorded.

The positive film 11 is then re-wound and the negative film 10 replaced by another negative film on which an action has been photographed. The screw 32 is then restored to its initial position to permit the spring 27 to restore the sound mask 18 into masking position in the light aperture, and the other screw 32 is operated so as to carry the sector 24 downwardly against the action of its spring 30 and through pinion 21 to carry the action mask out of the light aperture as illustrated in Figs. 5 and 6. The negative and positive films are then run through the same as before. This completes the operation.

In Fig. 7, the positive film 11 has the sound track printed thereon as shown at 40, in accordance with the first step as above described, while in Fig. 8, 41 designates the action. It is to be understood that the two printing steps may be reversed if desired.

It is to be understood also that changes may be made in the details of construction above described within the purview of my invention.

What I claim is:—

1. Printing apparatus for printing sound and motion pictures, comprising in combination a sound mask, an action mask, springs for retaining said masks in masking position, and a gear train for each mask for moving said masks out of operative position independently against the action of said springs and through said springs to restore the masks to operative position.

2. Printing apparatus for printing sound and motion pictures and comprising in com-

bination a pivoted sound mask and a pivoted action mask, a pinion carried by each mask, a gear sector for each pinion, said gear sectors being pivotally mounted, and means for rocking said sectors independently to effect independent movement of the masks out of and into operative position.

3. Printing apparatus for printing sound and motion pictures and comprising in combination a pivotally mounted sound mask and a pivotally mounted action mask, a pinion attached to each mask, a gear sector for each pinion, said sectors being pivoted intermediate their ends for independent movement, a spring for each sector engaging the same adjacent its outer end, for maintaining both masks in masking position, and screws manually adjustable for moving said masks independently out of operative position and to maintain them in such position against the action of said springs.

4. Printing apparatus for printing sound and motion pictures and comprising in combination a block, a sound mask and an action mask mounted therein on a transversely extending pivot, a pinion attached to each mask and mounted for rotation on said pivot, gear sectors mounted on a common pivot extending transversely of said block, said sectors meshing with said pinions, a pair of springs having one end engaging said block, their other ends engaging said sectors at the ends remote from said pinions to maintain the masks in masking position, and screws for moving said sectors independently against the action of said springs to move the masks selectively out of masking position and to maintain them in such position.

This specification signed this 21st day of Sept., 1929.
